UNITED STATES PATENT OFFICE.

ERNEST W. WHITE, OF MILFORD, OHIO, ASSIGNOR TO MEREDITH G. STANLEY, OF CINCINNATI, OHIO.

DINING-TABLE SERVICE-INDICATOR.

1,383,685.

Specification of Letters Patent. Patented July 5, 1921.

Application filed June 8, 1920. Serial No. 387,419.

To all whom it may concern:

Be it known that I, ERNEST W. WHITE, a citizen of the United States, and residing at Milford, in the county of Clermont and State of Ohio, have invented a new and useful Improvement in Dining-Table Service-Indicators, of which the following specification is a full disclosure.

My invention relates to a service indicator for dining-room tables, providing a silent signal for an attendant or waiter that his services are requested by a guest at a particular table.

It is an object of the invention to provide a small, ornate device, as a dining-table fixture or setting, extensible into a staff for attracting the attention of the attendant or waiter, indicating that a guest at the table is calling for his services.

Another object is to provide a construction of device for the purposes indicated as a post-like structure, which will be neat in appearance, simple in construction and operation, and which may be locked in a telescoped or compressed position, providing an arrangement of telescopic sections sprung for rendering the sections as a unit automatically extensible, and means for cushioning the sections at their limits of extensibility and providing for rigidity of the structure in its extended position.

An additional object is to provide a simple means for the attaching and positioning of the coöperative springs.

Additional objects and certain advantages will be set forth in the description and special reference is made to the drawings, forming a part of this specification, in which:

Figure 1 is a vertical sectional view of the device in its extended position.

Fig. 2 is a similar view in a depressed and locked position.

Fig. 3 is an enlarged fragmentary detail of one of the centering and attachment plugs, with the springs attached thereto.

Fig. 4 is a plan view of the plug shown in Fig. 3.

Referring to the drawings, 1 designates a base bored centrally for the reception of the lower tube section 2, of a telescopic column or post composed of additional sections 3, 4. The lower end of the section 2 is closed by

a disk 5, held in position by a cross-pin 6, the said disk being bored as at 7, to receive the lower end of an expansion spring 8. The lower end of the section 3 projects into the upper end of the section 2, the section 2 is of larger internal diameter than the external diameter of the section 3 and is annularly contracted as at 9 to loosely engage and guide the said section 3. A circular centering and attachment plug 10 is fastened within the lower end of the section 3, the same being composed of a disk portion 11, acting to center and guide the section 3 in its telescopic movement within the section 2 and to form a seat for a cushion spring, hereinafter described, and annularly interposed between the sections 2, 3. The plug 10 is secured within the end of the tube 3 by a cross pin 13 extending through the tube section and plug.

The construction of all plugs 10 is similar, as well as their placement at the lower end of each telescopic section of each of the sections comprised in the unit, and, therefore, the description of one is regarded as sufficient.

An opening 14 is provided in the disk portion 11 of the plug 10 and openings 15, 16, are drilled in the plug, the opening 16 receiving the upper terminal of the spring 8, and the openings 14, 15, receiving respectively the lower end of a cushion spring 19, 85 and the lower end of the expansion spring 20, of the section 3. Centrally of the disk portion of the plug 10, depends a stop-pin 21, designed to limit the downward movement of the section 3 by contact with the disk 5. A second plug is fitted within the lower end of the section 4, the same being similar in construction and function to the plug previously described, for the lower end of section 3. The upper end of the section 3 is contracted in a manner similar to the upper end of the section 2, and the lower end of the section 4 projects within the section 3. The top end of the section 4 is provided with a finishing cap 26, having a centrally depending pin 27, the lower end of which fits rigidly within the section 4, and the same is provided with a disk 28 beveled upon its lower side and designed to engage with a dog or catch 29, suitably mounted 100 within a housing at the top of the section 2,

to lock the sections of the telescopic display column in their compressed position, as shown in Fig. 2.

The relative expansion and contraction 5 sections of the springs 8 and 19 are such that the springs 19 act to arrest the movement of each section at a position which will prevent the lateral flexing or bending of the column at or near the extremities of the sections and 10 thus insure the rigidity of the column. The cushioning springs counteract the expelled force of the expansion springs at the extended limits of the sections relieving the device of any tilting or upsetting jars from 15 the rapid movement of the sections when released from their depressed telescopic position, and therefore tend to stabilize the device in its extended form.

Having described my invention, I claim:

20 1. In a telescopic display column, a tubular base section, a second tubular section telescopically mounted within said base section, expansion means within said base section for extending the said second telescopic 25 section, and means for limiting the extensive movement of the said second section, the said means comprising a cushion spring carried by the said second section and surrounding the same, and abuttingly engaging 30 the said base section to retard and limit the extensive movement of the expansion means within the said base section.

2. In a telescopic display column, a tubular base section, a second tubular telescopic 35 section arranged for extensible movement within said base section, a third tubular telescopic section arranged for extensible movement within said second section, expansion means within the base section and 40 within the said second section, and cushion means placed respectively between the base section and the second section, and between the second section and the said third section, the said cushion means acting to retard and limit the thrust of the said expansion means within the said base and second section.

3. In a telescopic display column, a tubular base section, a second tubular telescopic 50 section arranged for extensible movement within said base section, a third tubular telescopic section arranged for extensible movement within said second section, expansion means within the base section and with- 55 in the said second section, cushion means placed respectively between the base section and the second section, and between the second section and the said third section, the said cushion means acting to retard and 60 limit the thrust of the said expansion means

within the said base and second section, and means for locking the said second and third sections in a depressed position.

4. In a telescopic display column, a tubular base section, a second tubular telescopic 65 section arranged for extensible movement within said base section, a third tubular telescopic section arranged for extensible movement within said second section, expansion means within the base section and 70 within the said second section, cushion means placed respectively between the base section and the second section, and between the second section and the said third section, the said cushion means acting to retard and 75 limit the thrust of the said expansion means within the said base and second section, means for locking the said second and third sections in a depressed position, the said means consisting of a latch plate mounted at 80 the top of the third section, and latch means co-operating therewith, the said latch means being placed at the top of the said base section.

5. In a device of the class described, a 85 plurality of tubular telescopic sections telescopically and extensibly united, one section constituting a base section for supporting the structure, expansion means within said sections for automatically extending the 90 same, means for limiting the extension of said sections to positions of maximum rigidity, the said means comprising a disk-like plug fastened in the lower end of each telescopic section, springs above and below the 95 said plug and abutting the same, and cushion springs surrounding the lower portion of said sections, the same abutting the said plug and the upper contracted portions of each telescopic section.

100 6. A dining-table service indicator comprising an extensible post-like structure of a plurality of sections telescopically united, a base supporting said sections in a vertical plane, a spring housed within one section 105 and engaged with a second section for automatically extending said second section, and a spring between said sections for contracting the expelled force of said first-named spring at the limit of extended movement 110 of said second section, and means for locking said sections in their depressed position one within the other.

115 In witness whereof I hereunto subscribe my name, as attested by the two subscribing witnesses.

ERNEST W. WHITE.
